UNITED STATES PATENT OFFICE.

STACEY B. LINDLEY, OF INDIANAPOLIS, INDIANA, ASSIGNOR TO INDIANA CANNING MACHINERY COMPANY, OF INDIANAPOLIS, INDIANA, A CORPORATION.

MIXING AND STRAINING MACHINE.

Application filed March 20, 1925. Serial No. 17,017.

This invention pertains to a finishing machine employed for screening material such as tomatoes or the like for canning purposes, the principal features of the invention being also applicable for use in pulping machines of similar type.

The object of the invention is to improve upon finishing and pulping machines of this general character, one feature of which is to provide a baffle plate adjacent the inner end of the screen for preventing the incoming material from being thrown toward the middle of the screen and thereby being passed only over a portion thereof, the baffle plate forming a part of this invention being such as to cause the incoming material to be deposited upon the screen adjacent one end thereof so that it will be passed thereover for screening purposes from substantially one end to the other.

Another feature of the invention resides in the simplified discharge end mounting which permits ready removal of the discharge end plate, the support thereof as well as the bearing for the rotary shaft and discharge spout being contained integral in one piece so as to be readily removable and permit the removal of the screen and rotary brushes.

Another feature of the invention resides in the provision of a cleanout connection with the under pan for permitting the same to be cleaned and rinsed, allowing a discharge connection for the rinsing water independently of the connection for receiving and carrying away the pulp. This permits thorough cleansing of the pan without disconnecting the pulp delivery hose.

The full nature of the invention will be understood from the accompanying drawings and the following description and claims:

In the drawings, Figure 1 is a side elevation of the machine. Fig. 2 is an enlarged section taken on the line 2-2 of Fig. 1. Fig. 3 is an enlarged detail view taken on the line 3-3 of Fig. 2, with parts thereof broken away and removable. Fig. 4 is a sectional view showing the discharge and cleanout plugs and connections therefor. Fig. 5 is an end elevation of the discharge end of the machine. Fig. 6 is a section taken on the line 6-6 of Fig. 5. Fig. 7 is a lon-

gitudinal cross sectional view of Fig. 1 showing a portion of the screen mounted thereon.

In the drawings there is shown a finishing machine having a supporting frame 10 mounted on the legs 11. At the intake end of the machine there is an arched frame 12 having a bearing 13 adapted to receive a shaft 14 on the outer end of which is mounted a driving pulley 15 and idler pulley 16. Adjacent the arched end frame 12, but spaced therefrom, there is a frame member 17 including a plate 18 having an intake spout 19 formed integral therewith and opening therethrough. At the opposite end of the machine there is a pair of arms 20 rigidly secured on the frame 10, said arms being adapted to support in conjunction with the frame 17 an annular skeleton frame tapering slightly towards the intake end comprising the annular rings 21 and longitudinal bars 22, said bars 22 having one end secured to a ring 23 supported by the frame 17 and plate 18 and their other ends extending through the arms 20 for providing the protruding pins or projections 24.

Mounted within the skeleton frame so as to be rotatable therein, there is the usual set of longitudinally extending brushes 25 mounted on the shaft 14, said shaft being provided adjacent each end thereof with the radially extending sockets 26 formed integral with a sleeve 27 which is adapted to be keyed to said shaft so as to rotate therewith. The brushes 25 are secured adjacent their opposite ends within the U-shaped support 28 having a projection 29 adapted to extend into the sockets 26 and be located therein by the set screws 30, whereby said

brushes may be adjusted radially with respect to the shaft so as to engage the cylindrical or tapering screen mounted within the skeleton frame. Adjacent the intake end of the skeleton frame there is a baffle plate 31 disk-like in shape and having its periphery extending from the shaft to a point adjacent the bristles of the brushes 25, the periphery of said plate being cut away to provide recesses 32 for the reception of the brush supporting brackets 28. It will be noted that the baffle plate 31 is spaced appreciably from the intake end and from the ends of the brushes to form a limited re-

ceiving chamber and be in position to baffle the inflow of material received through the intake spout 19.

At the discharge end of the machine there is provided a discharge head 33 adapted to fit snugly to an end ring 34 of the skeleton frame which is supported upon arms 20, said discharge head 33 closing the discharge end of the skeleton frame and being provided with oppositely extending ears 35 having openings therein for fitting over the outwardly projecting pins 24 which accordingly align and support said plate in place. The shaft 14 is adapted to extend therethrough and be mounted in a bearing 36 which is supported by and forms a part of an arched end frame 37. The discharge head 33 is formed with a discharge opening 38 having a downwardly inclined lip 39 through which the unscreened produce will pass and be discharged, said head being rigidly mounted on the arched support 37 through the brackets 40. The arched support together with the bearing 36 and the head 33 is removably secured upon the frame by the screw bolts 41 having handles 42 and nuts 43. It will be obvious that the entire discharge head, bearing and frame support therefor may be readily withdrawn from the end of the machine by removing the screw bolts 41, after which the brushes and entire screen may be withdrawn from about the shaft 14.

Suspended from beneath the frame 10 there is an under pan 44 having its bottom sloping towards the discharge end of the machine, adjacent which end there is provided a pulp discharge opening 45 having a suitable end 46 for connecting therewith a hose 47 through which the pulp screened into the pan may pass into a suitable tank or the like. At the lowermost end of the pan and adjacent the opening 45 there is an opening 48 having a suitable fitting 49 for receiving the hose 50 through which washout water may pass to the sewer when the pan is being cleansed. A cap 51 is provided to be screwed into either opening, depending upon whether the machine is in use or being washed out. This arrangement facilitates the cleaning of the machine and pan and rinsing of the same, allowing a ready escape for the rinsing water without the necessity of altering the hose connections.

From the above it will be noted that with respect to the baffle plate, whereas heretofore the material entering the intake spout would be discharged and thrown substantially to the middle of the screen so that it would be screened through only a portion

thereof. By reason of this arrangement the rapid inflow of the material will be stopped and baffled by the plate 31 so as to drop onto the screen adjacent the intake end. The material will then be forced along the screen throughout the entire length thereof so as to obtain maximum screening efficiency.

It may be here noted that the scraping members, herein illustrated as brushes 25, may be in the form of paddles, whereby the contents of the screen are scraped about the inner surface thereof for screening purposes.

The invention claimed is:

1. In a screening machine of the character described, the combination with a supporting frame, a substantially cylindrical screen, brushing members rotatably mounted within said screen, a shaft for rotating said members, and means for driving said shaft, of a unitary end mounting provided therefor, said mounting comprising an end plate adapted to close the discharge end of said screen and provide a discharge opening for the unscreened contents thereof, a support for said mounting adapted to be removably secured to said frame, and a bearing formed on said support for receiving one end of said shaft and supporting the same, whereby upon the removal of said unitary mounting the entire discharge end of said screen may be opened and the brushing members and screen removed.

2. In a screening machine of the character described, the combination with a supporting frame, a substantially cylindrical screen, brushing members rotatably mounted on said screen, a shaft for rotating said members, and means for driving said shaft, of a unitary end mounting provided therefor, an end head adapted to fit over the discharge end of said screen for closing the same, said head being provided with a discharge opening through which the unscreened contents thereof may pass, outwardly extending pins formed integral with said head adapted to be engaged with said frame for aligning and positioning the head thereon, an arched support for said head having its ends removably secured to the sides of said frame, and arching over said discharge opening, and a bearing provided on said support for receiving and supporting one end of said shaft, whereby upon the removal of said support and head the scraping members and screen may be bodily removed from said shaft.

In witness whereof, I have hereunto affixed my signature.

STACEY B. LINDLEY.
